UNITED STATES PATENT OFFICE

ALBERT N. ERICKSON, OF ELMHURST, NEW YORK, ASSIGNOR TO UNION CARBIDE COMPANY, A CORPORATION OF VIRGINIA

HEAD FOR GAS DETECTORS

Application filed December 5, 1927. Serial No. 237,971.

This invention relates to detectors for combustible gases and especially to means for providing an improved head for containing the resistance element thereof.

5 In my copending application, Ser. No. 181,227, filed April 5, 1927, I have disclosed an apparatus for detecting the presence of combustible gases in an atmosphere. In this device a filament of a suitable material, such as 10 platinum, is heated to such a temperature that if any combustible gas be present in the atmosphere it will be oxidized. This oxidation causes a raising of the temperature of the filament and this rise in temperature is 15 measured in any suitable manner, preferably by noting the change in the resistance of the filament.

This invention has for its object the improvement of the head containing such a 20 filament and especially the provision of means for making the instrument more accurate. Another object is to provide a head in which the current will automatically be cut off from the filament when the protective bonnet is 25 removed.

These and other objects of my invention will be evident from the following specification having reference to the accompanying drawings in which:

30 Figure 1 is a vertical cross section through a detector head constructed in accordance with my invention;

Figure 2 is a perspective view of the bonnet locking ring, the ring being inverted to show 35 the contacts carried thereby;

Figure 3 is a perspective view of the filament cartridge supporting member;

Figure 4 is a plan view of the top of the bonnet;

40 Figure 5 is a vertical cross section of another embodiment of my device; and

Figure 6 is a section on line 6-6 of Figure 5.

In my application, Serial No. 181,227, above 45 referred to, I have disclosed an apparatus in which a current of electricity is passed through a filament held in a cartridge, the cartridge being of skeleton form so that the atmosphere may come into intimate contact 50 with the filament. The cartridge is secured

in a head and surrounded by screens for the purpose of preventing the propagation of the flame from the filament to the surrounding atmosphere and is further protected by a bonnet in order that the screen may not be 55 accidentally injured. The filament is heated to such a temperature that any combustible gases in the surrounding atmosphere will be oxidized and the change in temperature of the filament measured as disclosed in that application. I prefer to measure this change in 60 temperature by noting the change of resistance of filament, this change in resistance being measured by any suitable manner, such as by a Wheatstone bridge.

65 In the apparatus shown in Figures 1 to 4 inclusive a detector head 10 is mounted on the staff 11. The head consists of a socket 12 and a protective bonnet assembly 13. The bonnet assembly comprises an outer bonnet 14, a plurality of screens 15, said screens being provided with flanges at their base, and a locking ring 17. This locking ring is provided with contact members 18 for a reason which will be more fully set forth herein. The 70 socket 12 contains a cartridge supporting member 19 which is made of insulating material. This cartridge supporting member is preferably made in the shape of a spool, the upper flange 21 being smaller in diameter 75 than the lower flange 22, which carries two pairs of contacts 23, 24 and 25, 26 for engagement with the contact pieces 18. The upper flange 21 carries a pair of posts 27, 28, these 80 posts being provided with projections 29 for holding a cartridge 31. A link 32 of non-conducting material slides on the posts 27 and 28 forcing the ends together to grip the cartridge 31.

85 This form of my invention is assembled as 90 follows: The socket 12 is secured to the staff 11 and a pair of conductors are led into the socket through a hole 38 in the staff. One of these conductors is connected to the contact 95 23 and the other to the contact 26. The contact 24 is connected to the support 27 and the contact 25 to the support 28 through a central opening in the spool shaped supporting member. The locking ring 17 is then placed into position, the contact members 18 passing 100

through slots 33 in the upper flange 21. The ring is then rotated 90° so that the members 18 close the circuit between contacts 23 and 24 and between the contacts 25 and 26. The screen members 15 are then placed in position above the locking ring 17 and the bonnet 14 is screwed down, the interior threaded portion thereof engaging the outer threaded portion 34 of the socket 12 and the outer threaded portion 35 of the locking ring 17. When the bottom of the bonnet 14 bears against shoulder 36 on the socket 12, screws 37 are inserted through the bonnet and locking rings to hold these in fixed relation. Upon unscrewing the bonnet the entire protective bonnet assembly, including the screens and locking ring, is removed as a unit, the flange of the screens being locked between the locking ring and the shoulder on the inside of the bonnet. The purpose of initially assembling the detector head in this manner is to assure the engagement of the contacts 18 with the contact pieces 23, 24, 25 and 26 when the bonnet is screwed on.

It will be seen that when the bonnet assembly is unscrewed to permit the renewal of the cartridge 31 containing the filament, the contacts 18 are separated from the contact pieces 23, 24, 25 and 26 thus insuring that the heated filament is not exposed unprotected to the atmosphere.

The cartridge 31 contains the filament which is heated to cause oxidation of the combustible gas. This filament is preferably a platinum wire and I have found that a length of 1½ inches of wire of a diameter of .005 inches coiled on $\frac{1}{16}$ inch rod and stretched in a holder whose ends are $\frac{5}{8}$ inches apart is very satisfactory. While this cartridge or holder may be placed in any position I have found that for some circumstances it is preferable to have the holder arranged horizontally. This is especially true when it is desired that the detector head shall permit of tipping. If the holder be placed vertically and the head tipped the reading may be diminished by an amount corresponding to as much as 0.75% of methane present in the atmosphere being tested. If the holder is arranged horizontally the head may be tipped, taking care to still maintain the holder horizontally. In this case there will be no change in the reading. Should the head be tipped in such a direction as to cause the holder to tend to assume a vertical position or should the head, after being tipped with the holder horizontal, be rotated, there will be a possibility of error but this would show a greater amount of combustible gas than is actually present.

In order to insure that the holder is kept horizontal, the top of the bonnet is provided with a suitable marking 39 which bears a fixed relation to the filament holder. While various forms of indicia may be used I have

found a line parallel to the filament holder to be satisfactory. This bonnet may be of any suitable material to protect the screens and is provided with means whereby the atmosphere may have free access to the filament. A suitable construction for this bonnet is formed by cutting a series of short parallel slots in a cylinder of brass, aluminum or other suitable material and deforming the metal inwardly between pairs of adjacent slots as is clearly shown in Figure 1.

In Figures 5 and 6 I show another embodiment of my invention. This embodiment comprises a socket 41 and a bonnet assembly 42, the bonnet assembly consisting of a bonnet 43, screen 44 and a locking ring 45. The socket contains posts 46 and 47 for holding a filament cartridge therebetween, the post 46 being movable to permit of the replacement of the cartridge. In the socket are two curved slots 48 of T-shaped cross section, these slots being provided with enlargements in the top portion thereof at one end as shown at 49. At the opposite end of the slots are mounted pairs of spaced contacts 51, 52 and 53, 54. One of the contacts, as 52, is connected to the post 46 and one of the other pair, as 53, is connected to the post 47. The other two contacts, 51 and 54, are connected to the conductor pair which is led in through the hole 38 in the staff 11. The bonnet carries a pair of studs 55. Each stud carries an insulating washer 56 which is L-shaped in cross section. Mounted on this washer is a contact making piece 57.

This form of my invention is assembled as follows. The filament holder is secured between the posts 46 and 47 and the bonnet assembly is secured to the socket by causing the studs 55 to enter the enlargement 49 in the slots 48. The bonnet assembly is then rotated 90° on the socket, locking these together and closing the circuit between the contacts 51, 52 and 53, 54.

I claim:

1. A head for a detector of combustible gases, comprising a base for supporting a resistor, an electrical circuit including said resistor, a protective member for said resistor and means carried by said protective member for closing said circuit.

2. A head for a detector for combustible gases comprising a base, means for supporting a resistor on said base, spaced contacts on said base, a protective member surrounding said resistor and engaging said base and contact pieces carried by said protective member for electrically connecting said contacts.

3. A head for a detector for combustible gases comprising means for supporting a resistor, terminals on said supporting means electrically connected to said resistor, terminals for an external circuit carried by said supporting means and a protective

member for said resistor, said protective means being provided with means for completing the circuit between said resistor terminals and said external circuit terminals.

- 5 4. A head for a detector of combustible gases comprising a base, means on said base for supporting a resistor and a bonnet assembly, said assembly comprising a protective bonnet, a plurality of screen members
10 within said bonnet and a locking ring, said bonnet assembly being provided with means for closing a circuit to said resistor.

In testimony whereof, I affix my signature.

ALBERT N. ERICKSON.
